United States Patent [19]

Takizawa et al.

[11] Patent Number: Des. 427,977

[45] Date of Patent: ** Jul. 11, 2000

[54] **PIEZOELECTRIC CONVERSION TYPE SEMICONDUCTOR DEVICE**

[75] Inventors: **Takashi Takizawa, Kawasaki; Tatsuya Itoh; Naoshi Tsukada**, both of Akita, all of Japan

[73] Assignee: **Fujikura Ltd.**, Tokyo, Japan

[**] Term: **14 Years**

[21] Appl. No.: **29/106,663**

[22] Filed: **Jun. 18, 1999**

[51] LOC (7) Cl. **13-03**

[52] U.S. Cl. **D13/182**

[57] CLAIM

The ornamental design for a piezoelectric conversion type semiconductor device, as shown.

DESCRIPTION

FIG. 1 is a front, top and right side perspective view of a piezoelectric conversion type semiconductor device, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof;
